UNITED STATES PATENT OFFICE

PAUL HÖSEL, OF CHARLOTTENBURG, GERMANY, ASSIGNOR TO GENERAL ELECTRIC COMPANY, A CORPORATION OF NEW YORK

BALANCED VALVE

Application filed February 17, 1928, Serial No. 255,131, and in Germany March 1, 1927.

The present invention relates to balanced valves such as are used, for example, to control the flow of elastic fluid.

The object of the present invention is to provide an improved construction in a balanced valve possessing certain advantages as hereinafter pointed out, and for a consideration of what I believe to be novel and my invention, attention is directed to the accompanying description and the claims appended thereto.

In the drawing, the figure is a sectional view of a balanced valve embodying the invention.

Referring to the drawing, 1 indicates a valve casing having an inlet opening 2, a discharge opening 3, and walls forming valve seats 4 and 5. Valve seats 4 and 5 are oppositely arranged relatively to each other, the valve seat 4 facing upwardly and the valve seat 5 facing downwardly. Extending across the valve casing is a hollow guide rod 6 on which valve disks 7 and 8 are slidably mounted. Valve disks 7 and 8 are adapted to engage valve seats 4 and 5 respectively. Valve disk 7 is connected to the outer end of an arm 9 which is fixed on a shaft 10 extending transversely of casing 1 and pivotally mounted in walls of the casing. Valve disk 8 is connected to the outer end of the arm 11 fixed on a shaft 12 pivoted in walls of casing 1. Shafts 10 and 12 are connected together outside casing 1, by a rod 13 which is connected at one end to the end of an arm 14 fixed on shaft 10 and at the other end to the end of an arm 15 fixed on shaft 12.

Fixed on shaft 10 is a lever arm 17 to the free end of which an actuating rod 18 is connected. Rod 18 may lead to any suitable type of valve actuating mechanism adapted to be either manually or power controlled.

In rod 13 is a turn buckle 16 for use in adjusting the length of the rod. By adjusting the turn buckle 16 it will be seen that the valve disks can be adjusted relatively to each other so that both engage their seats when the valve is closed. In adjusting the valve disks the one valve disk can be held closed by means of the operating rod 18 after which

the turn buckle may be adjusted to bring the other valve disk to its closed position.

Valve disks 7 and 8 are provided with separate balancing pistons, the balancing piston for valve disk 7 being indicated at 19 and 55 the balancing piston for valve disk 8 being indicated at 20. In the present instance, balancing pistons 19 and 20 are shown as telescoping one within the other so that in substance the balancing piston of one valve disk 60 forms a cylinder for the balancing piston of the other valve disk. In guide rod 6 are openings 21 connecting the space within balancing pistons 19 and 20 to the inlet side of valve casing 1.

With the foregoing arrangement, it will be seen that when rod 18 is moved upward valve disks 7 and 8 are both moved toward their seats and that when rod 18 is moved downward valve disks 7 and 8 are both moved 70 away from their seats. Since valve seats 4 and 5 are oppositely arranged, valve disks 7 and 8 are arranged to move in opposite directions. When valve disks 7 and 8 are both on their seats, it will be seen that the pressure 75 acting on the outer surfaces of valve disks 7 and 8 is counter-balanced by the pressure inside balancing disks 19 and 20 so that when seated the valve disks are balanced. This means that they may be readily moved from 80 their seats when it is desired to open the valve so that no pilot valve arrangement such as is used ordinarily with valves of this type, is required.

When the valve disks are opened, it will be 85 seen that the elastic fluid flows through both of them in the same manner; that is, it flows under the valve disks and through the valve openings. This means that the flow past the two valve disks is alike. By this means the 90 formation of eddies in the flow is to a great extent eliminated so that a smoother and more even passage of fluid through the valve openings is obtained.

In the usual type of balanced valve structure the valve seats are similarly arranged and the valve disks are rigidly fastened together and both move in the same direction. When such a valve is open, it will be seen 95 that at the one opening the flow of fluid is 100

under the valve disk and through the opening while at the other opening, it is through the opening and against the underside of the valve disk. As a result the flow through the two openings is not alike and that at the one opening the fluid after flowing through the opening strikes against the underside of the valve disk and is diverted by the valve disk. This tends to set up eddies in the flow. By 5 the construction of the invention wherein the valve disks are oppositely arranged and the valve disks move in opposite directions in opening, the difficulty just referred to is avoided.

10 15 In accordance with the provisions of the patent statutes, I have described the principle of operation of my invention, together with the apparatus which I now consider to represent the best embodiment thereof, but 20 I desire to have it understood that the apparatus shown is only illustrative and that the invention may be carried out by other means.

What I claim as new and desire to secure 25 by Letters Patent of the United States, is:

1. In a valve structure, a valve casing, walls in the casing which define oppositely-arranged valve seats, valve disks for said seats, means for moving said valve disks simultaneously toward and away from said valve seats, and balancing pistons for said valve disks.
2. In a valve structure, a valve casing, walls in the casing which define oppositely-arranged valve seats, valve disks for said seats, means for moving said valve disks simultaneously toward and away from said valve seats, and telescoping balancing pistons for said valve disks.
3. In a valve structure, a valve casing, walls in the casing which define oppositely-arranged valve seats, valve disks for said seats, means including a rod connecting said two valves together, means for adjusting the length of said rod, means for moving the rod to simultaneously move said valve disks toward and away from their seats, and balancing means for said valve disks.
4. In a valve structure, a valve casing, walls in the casing which define spaced oppositely arranged valve seats, valve discs for said seats, means for moving said valve discs simultaneously toward and away from said valve seats, and telescoping balancing pistons connected to said valve discs and arranged between said seats.

In witness whereof I have hereunto set my hand this 31st day of January, 1928.

PAUL HÖSEL.
